UNITED STATES PATENT OFFICE.

HEINRICH SCHWARZENBACH AND GOTTLIEB LIER, OF ZURICH,
SWITZERLAND.

DOBBY FOR LOOMS FOR WEAVING.

SPECIFICATION forming part of Letters Patent No. 763,432, dated June 28, 1904.

Application filed September 2, 1902. Serial No. 121,907. (No model.)

To all whom it may concern:

Be it known that we, HEINRICH SCHWARZENBACH and GOTTLIEB LIER, citizens of the Republic of Switzerland, both residing at Zurich, Switzerland, (whose post-office addresses are, respectively, Langnau, near Zurich, and 12 Malzgasse, Zurich, aforesaid,) have invented new and useful Improvements in Dobbies for Looms for Weaving, of which the following is a specification.

Our invention has for its object the construction of a dobbay in which the usual cards are dispensed with and substituted by a cylinder adapted to be displaced axially forward and backward and formed with perforations adapted to receive pegs which actuate the needles and catches in accordance with the changes required. We attain these objects by the mechanism illustrated in the accompanying drawings, in which—

Figure 1 is a front view; Fig. 2, a side view from the left, and Fig. 3 a partial side view from the right.

Similar characters refer to similar parts throughout the several views.

In carrying out our invention we secure upon the shaft 1, which is mounted on the frame side *c* of the dobbay and may be rotated from the loom by means of chain-gearing, a worm-wheel 2 in gear with another worm-wheel, 3, also situated on the frame side *c*. Upon the boss of the worm-wheel 3 is secured the wheel 4 in gear with the spur-wheel 5, secured upon a shaft 6, passing crosswise through the dobbay. This shaft carries at its other end a spur-wheel 7 in gear with the spur-wheel 9, mounted on the frame side *d* and carrying a stud 8 and a disk 11, furnished also with a stud 10, which latter actuates the star-wheel 12, secured to one end of a shaft 120, mounted in a bearing on the frame side *d* and upon the other end of which is employed the spur-wheel 13 in gear with the spur-wheel 14, Fig. 3, secured to the cylinder 15, mounted in the dobbay sides axially displaceable. This cylinder has around its periphery rows of holes adapted to receive the pegs 16, which actuate the needles and catches, Fig. 2, arranged as usual. The shaft of the cylinder 15 and the star-wheel 12

have each a grooved collar or boss 17 and 18, respectively, in the grooves of which engages a rod 19, carried by two lever-arms 21, fulcrumed to the shaft 20, mounted on the frame side *d*, to which shaft is secured the lever 22, having a stud 23, engaging in the groove 24 of the cam 25, secured upon the shaft 26, extending across the dobbay. At the driving side of the dobbay (worm-wheels 2 and 3) the shaft 26 has secured a star-wheel 27, placed under the influence of a spring 44 and axially displaceable. In one position this star-wheel is adapted to be rotated from the shaft 6 by means of the stud 47 on the disk 45, secured on the said shaft and in the other (position in Fig. 1) prevented from rotating by the disk 46, also secured upon the shaft 6. This star-wheel has a grooved boss 28, in the groove of which engages a forked lever 30, secured upon the shaft 29, which is parallel with the frame side *c*. This shaft carries also the lever 31, bearing against a cam 32, secured upon the driving-shaft 1. Upon the shaft 29 is further secured the lever 33, to which is jointed the rod 34, situated at the back of the dobbay and the other end of which forms a catch hooking in the position of the dobbay parts shown in the drawings onto the bracket 35, secured to the frame side *c*. A spring 50 presses the rod 34 against the outer needle pair 51 at one side of the dobbay.

Upon the shaft 6 are secured the cams 36, against which bear the angular levers 37, fulcrumed to the sides of the dobbay. The said angular levers carry a rod 38, extending across the dobbay, to which are hinged the arms 40, furnished with studs 39 and the ends of which engage between the rod 41, by which the frame sides are connected together, and the adjacent ends of the needles.

The knives of the dobbay are moved through the medium of the rocking lever 42 and the rods 43, motion being imparted to it by a rod eccentrically connected with the driving or chain wheel of the dobbay.

The dobbay described operates as follows: By means of the wheels 45 and the shaft 6 rotary motion is transmitted from the said worm-wheels to the disk 11 and through the

needle-operated catches and pegged cylinder actuating the needles, a shaft mounted in bearings adjacent to the said cylinder, cams secured upon the said shaft, angular levers 5 carrying jointly a shaft, studded levers hinged upon the said shaft, a stationary rod opposite the inner ends of the said needles between which and the latter the free ends of the said hinged lever reach, the said cams being adapted 10 to actuate the said angular levers and cause the studs of the said hinged levers to meet the pegs of the opposite cylinder row and thereby actuate the said needles, all combined substantially as and for the purpose set forth.

15 5. In a dobby for looms for weaving with needle-operated catches and pegged cylinder actuating the needles, a shaft mounted in bearings at the side of the dobby, a lever secured thereto at one end, an arm at the other and between 20 the same a forked lever, a shaft mounted at a right angle thereto, a star-wheel se-

cured at one end and a cam-grooved disk at the other end of the latter, a rod jointed to the first-named lever having a hook-shaped end, a stationary bracket to receive the same and a 25 cam secured upon the driving-shaft, the said rod being adapted to be pushed off the said bracket by one of the said needles and thus cause the said forked arm to bring the said wheel into position for being rotated and the 30 said cam to be depressed afterward by the said arm and thereby cause the said star-wheel and in the meantime the said rod to be brought into their former position, all combined substantially as and for the purpose set forth. 35

In witness whereof we have hereunto set our hands in presence of two witnesses.

HEINRICH SCHWARZENBACH.
GOTTLIEB LIER.

Witnesses:

CARL MÜLLER,
A. LIEBERKNECHT.
